a corporation of MarylandNo Drawing. Application November 17, 1934,
Serial No. 753,545

10 Claims. (Cl. 167—68)

This invention relates to a method of producing bland petroleum-hydrocarbon solutions of chemically pure metal abietates, based on the present accepted structural formula of abietic acid salts

15 with the assistance of alkyl esters of abietic acid or alkyl esters of natural wood resin, essential oils or their principal chemical constituents.

By dissolving the colloidal metal abietate in selected essential oils or their principal constituents, dispersing this solution in abietic acid alkyl ester or resin acid alkyl ester or hydrogenated alkyl ester of abietic acid, and then adding the petroleum hydrocarbons, a solution is obtained.

20 Non-water soluble metal abietates, particularly silver, bismuth and mercury, are known to be soluble in common solvents like benzene, ether, acetone, carbon tetrachloride, chloroform, etc. These solvents are not adaptable for therapeutical or medical use as they are too irritating on exposed body surfaces or mucous membranes.

25 In accordance with our present invention, we propose these compounds, which we have found to possess effective bacteriological properties, for therapeutic or medicinal uses.

Because of the necessity of using bland oils or bland mixtures for that purpose, we attempted to employ liquid petrolatum U. S. P. X (petroleum hydrocarbons of U. S. P. X standard purity), but 30 found they could not be used for that purpose because the metal abietates are not soluble in those oils.

35 We discovered that by dissolving or dispersing the metal abietate in some of the following essential oils or their main constituents, intermiscible with petroleum hydrocarbon oils, the antiseptic efficiency was not altered.

40 A selected list of the most economical or most prominent types of those oils are as follows, and 45 were found to serve that purpose.

Citrus oils (lemon, orange, etc.)

Turpentine

Oil pine

Oil copaiba

Oil eucalyptus

5 Eucalyptol

Oil camphor

containing as main constituents:

Terpines

10 Sesquiterpes

Terpin esters

Terpin anhydride

They dissolve metal abietates and are also miscible with esters of abietic acid and petroleum hydrocarbons.

15 We found further that to facilitate this dissolving process, the use of purified alkyl esters of natural wood resin or alkyl esters of abietic acid in addition to the petroleum oils, is of good advantage to produce clear solutions, without impairing the antiseptic properties of the compounded mixture. These alkyl esters are good solvents for all petroleum hydrocarbons. We found that they were intermiscible with the solutions of metal abietates in organic chemicals or 20 essential oils as explained before.

25 We found that 20% to 45% of the metal abietates, particularly silver abietate, may be kept in the essential oils or related chemical substances 30 in solution.

For practical purposes, we found that not more than 2% metal abietate is necessary in the compounded mixture to give the antiseptic efficiency required for therapeutic use. To dissolve that 35 amount of metal abietate in the essential oils or related chemical substances will require not less than 30% of abietic acid esters to 70% petroleum hydrocarbons.

(1) The efficiency in regard to antiseptic action 40 can be easily demonstrated by using the petri dish agar medium penetration test, the so-called Himebaugh technique, as described in Bulletin No. 198, December, 1931, of the U. S. Department of Agriculture, using as the organism of experimentation, *staphylococcus aureus*, the well-known standard organism for testing bactericidal efficiency.

(2) Or the yeast fermentation inhibition, using 45 a technique similar to the Pilcher, Sollman and 50

Leech method by measuring their inhibiting effect on yeast-sugar fermentation.

To illustrate on a sample, our method of preparing and compounding, we proceed substantially as follows, 1-abietic acid was made according to the directions of Steele (J. Am. Chem. Soc., 44, 1333, 1922) from American wood resin. This product is recrystallized several times from methanol and dried in vacuo. This purified acid is converted into the potassium salt of the 1-abietic acid and then converted into the silver salt. 0.2 gr. silver abietate, after purification, is triturated with 0.8 cc. eucalyptol U. S. P. until a clear solution is obtained. Then 30 cc. abietic acid methyl ester is added; preferably for better color and stability, vacuum distilled abietic acid methyl ester or abietic acid methyl ester hydrogenated is used, and now, under constant stirring, 69 cc. liquid petrolatum is mixed in. After allowing to stand a few days and filtering, a clear stable, nearly water-white solution is obtained.

The scope of this invention is to be determined by reference to the following claims, said claims to be interpreted as broadly as possible, consistent with the state of the art.

We claim as our invention:

1. A bland therapeutic composition containing an abietate of a metal selected from the group consisting of silver, bismuth, mercury and zinc dissolved in an essential oil which is a solvent for said abietate and dispersed in a lower alkyl ester of abietic acid, and a petroleum hydrocarbon.

2. A bland therapeutic composition containing an abietate of a metal selected from the group consisting of silver, bismuth, mercury and zinc dissolved in an essential oil which is a solvent for said abietate and dispersed in a lower alkyl ester of abietic acid, and liquid petrolatum.

3. A bland therapeutic composition containing a silver abietate dissolved in an essential oil which is a solvent of said abietate and dispersed in a lower alkyl ester of abietic acid, and liquid petrolatum.

4. A therapeutic composition containing a

mercury abietate dissolved in eucalyptus oil and dispersed in a lower alkyl ester of abietic acid, and a petroleum hydrocarbon.

5. A therapeutic composition containing a bismuth abietate dissolved in eucalyptus oil and dispersed in a lower alkyl ester of abietic acid, and liquid petrolatum.

6. A therapeutic composition containing an abietate of a metal selected from the group consisting of silver, bismuth, mercury and zinc dissolved in eucalyptol and dispersed in a lower alkyl ester of abietic acid, and a petroleum hydrocarbon oil.

7. A bland therapeutic composition containing an abietate of a metal selected from the group consisting of silver, bismuth, mercury and zinc dissolved in an essential oil which is a solvent of said abietate and dispersed in a hydrogenated alkyl ester of abietic acid, and liquid petrolatum.

8. A bland therapeutic composition containing an abietate of a metal selected from the group consisting of silver, bismuth, mercury, and zinc dissolved in an essential oil which is a solvent of said abietate and dispersed in a hydrogenated methyl ester of abietic acid, and liquid petrolatum.

9. The method of preparing a bland therapeutic composition which consists in dissolving an abietate of a metal selected from the group consisting of silver, mercury, bismuth, and zinc, in an essential oil which is a solvent for said metal abietate, adding a lower alkyl ester of abietic acid, and, under constant stirring, incorporating a petroleum hydrocarbon oil.

10. The method of preparing a bland therapeutic composition which consists in dissolving an abietate of a metal selected from the group consisting of silver, mercury, bismuth, and zinc, in an essential oil which is a solvent for said metal abietate, adding a lower alkyl ester of abietic acid and, under constant stirring, incorporating a liquid petrolatum.
